UNITED STATES PATENT OFFICE.

ERLAND JUSELIUS, OF BROOKLYN, NEW YORK.

LOCK.

1,275,938.

Specification of Letters Patent. Patented Aug. 13, 1918.

Application filed August 11, 1917. Serial No. 185,706.

To all whom it may concern:

Be it known that I, ERLAND JUSELIUS, a citizen of the United States, and a resident of New York, borough of Brooklyn, 5 county of Kings, and State of New York, have invented a certain new and useful Improvement in Locks, of which the following is a full, clear, and exact specification.

This invention relates more particularly 10 to a class of door locking devices.

My invention has for its object primarily to provide a lock designed to be employed on the doors especially of buildings and elsewhere whereby each door may be locked in a manner 15 against being surreptitiously opened by preventing the lock from being operated exteriorly of the door when closed by forcing a knife blade, or similar implement between the door and its frame as is incident to the 20 methods frequently used to accomplish burglaries, and which is of a simple, efficient and durable construction adapted to be made for use as a rim or mortise lock. The invention consists essentially of a casing adapted 25 to be applied on a door in opposition to two sockets provided in the frame of the door. In the casing is a spring actuated bolt arranged so that one of its ends is normally disposed exteriorly of the casing for being 30 removably seated in one of the sockets of the frame to lock the door when closed, and this bolt may be operated by a key or otherwise for being yieldingly guided within the casing to unlock the door. Also yieldingly 35 movable in the casing between the bolt and the exterior of the door is a spring actuated shield element which is releasably held normally within the casing, and which is adapted to be sprung when the door is closed 40 whereby one of its ends will extend from the casing for removable insertion in the second socket of the door frame to protect the bolt from being operated by an instrument when forced between the door and its 45 frame.

Other objects of the invention are to provide means for operating the spring element whereby it will be yieldingly forced outwardly of the casing on closing the door; 50 and to provide means on the shield element

engageable by the bolt so that the element will be guided inwardly of the casing when the bolt is similarly operated.

With these and other objects in view the invention will be hereinafter more particularly described with reference to the accompanying drawings, which form a part of this specification, in which similar characters of reference indicate corresponding parts in all the views, and will then be pointed out 55 in the claims at the end of the description.

In the drawings, Figure 1 is a fragmentary view showing a door with one form 60 of lock embodying my invention applied thereto.

Fig. 2 is a view looking downward on the top edge of the lock.

Fig. 3 is a view looking into the casing of the lock showing its bolt in a position with one of its ends disposed exteriorly of the 70 casing.

Fig. 4 is a similar view, partly broken away, showing the bolt positioned within the casing, and

Fig. 5 is a sectional view, partly in detail, 75 taken on the line V—V of Fig. 3.

The device, or lock has a casing 10 which is preferably substantially rectangular in shape to provide a front wall 11, rear wall 12, bottom wall 13, top wall 14, and side 80 walls 15 and 16 both of which may be removably fastened to the other walls. The casing may be made of a suitable size so as to be embedded, or mortised in the door, as 17, of a building or elsewhere in opposed 85 relation to two adjacent sockets, as 18 and 19, provided in the frame, as 20, of the door, or the casing may be made of a size and shape for use as a rim lock on the inner surface of the door.

In the central parts of the upper portions of the side walls 15 and 16 of the casing 10 is journaled a transverse shaft 21 of a length 90 so that both of its ends extend beyond these side walls. On the end of the shaft protruding beyond the side wall 15 may be provided a tumbler barrel, as 22, of any well known, or preferred type whereby a suitable key may be employed to operate the lock, 95 and on the end of the shaft extending be- 100

yond the side wall 16 may be mounted a knob, as 23, to allow the shaft to be rotated by the hand of a person when desired.

Interiorly of the casing 10 between the bottom wall 13 and the top wall 14 as well as being spaced from the rear wall 12 is a stationary transverse partition 24 of a width to fit closely between the side walls 15 and 16, and in the central part of the edge of this partition which is adjacent to the wall 15 is an elongated recess 25, while in the central part of the opposite edge of the partition is a similar elongated recess 26. In the front wall 11 of the casing adjacent to the side wall 15 is an elongated opening, as 27, and also in this front wall adjacent to the side wall 16 of the casing is a larger opening, as 28, while through the front wall between the openings 27 and 28 is a hole 29.

Within the casing 10 is a bolt 30 which may be formed with a flat elongated substantially rectangular plate 31 arranged in slideable contact with the side wall 16 of the casing as well as being of a length so as to be guided back and forth through the opening 28 of the front wall of the casing and through the recess 26 of the partition 24. On the underside of the end of this plate of the bolt at its end adapted to be moved inwardly and outwardly of the opening 28 may be a head, as 32, which is also movable inwardly and outwardly of the opening 28, and the part of this head together with the end of the plate thereabove which are movable outwardly of the opening may be beveled, as shown, according to the bolts of locks of this class. The head 32 and the plate 31 may be integrally formed, and projecting interiorly of the casing from this head as well as depending from the underside of the plate 31 is a lug 33, while also depending from the center of the plate in spaced relation to the partition 24 is another lug 34.

The bolt 30 is normally forced yieldingly in a direction so that its head 32 is disposed outwardly of the casing 10 so as to be removably seated in the socket 18 of the frame of the door by a spring, as 35. The spring 35 may be in the form of a rod, or strip of spring metal having one of its ends secured, at 36, to the wall 13 of the casing while the second end of the rod is in movable contact with the lug 33 of the bolt, and this spring is tensioned so as to normally force the bolt outwardly of the casing. With the bolt 30 being operatively arranged in this manner its head 32 will contact with the frame of the door when moved to a closed position, and in turn the bolt will be guided interiorly of the casing 10 against the tension of the spring 35 so that the spring will reversely act to cause the head of the bolt to be removably seated in the socket 18 of the frame of the door when entirely closed.

The door will then be locked, and serving as means to operate the bolt whereby the door may be unlocked on the shaft 21 interiorly of the casing is provided a roll-back as 37. The roll-back 37 may be in the form of a curved substantially triangular plate, as shown, having its wide end held on the shaft so that its tapered curved end normally contacts with the lug 34 of the bolt 30. When the bolt 30 is sprung outwardly of the casing, as explained, for locking the door this roll-back will be rotatably swung in a like direction, and when the bolt has moved a determined distance it is releasably held against further movement by limiting the rotary movement of the roll-back by a pin, as 38, which is provided to protrude from the side wall 16 of the casing in the path of movement of the roll-back. To operate the bolt for unlocking the door, the shaft 21 is rotated by means of a key inserted in the barrel 22 or by rotating the knob 23 for swinging the roll-back 37 in a direction toward the rear wall of the casing, as shown in Fig. 4. The bolt will thereby be moved interiorly of the casing against the tension of the spring 35 so that the door may be opened.

In order to protect the bolt 30 from being surreptitiously operated when the door is locked by passing an instrument between the door and its frame, I provide a shield element, as 40. This shield element is preferably in the form of an elongated substantially rectangular plate which is arranged interiorly of the casing on the side wall 15 so that one of its ends may be guided outwardly and inwardly of the opening 27 of the wall 11 of the casing. The shield 40 is of a length similar to the length of the bolt 30, and extending from the central part of the shield toward the bolt 30 is a lug 41, while centrally of one of the edges of the shield is an elongated recess to provide two spaced shoulders, as 42 and 43. The shield element 40 may be yieldingly forced outwardly of the casing by a spring, as 44, which is preferably of the form of a rod, or strip of spring metal having one of its end parts secured, at 45, interiorly of the wall 14 of the casing, while its other end is in movable contact with the lug 41, and this spring tends normally to force the shield outwardly of the casing. The shield element 40 is normally locked releasably within the casing and to accomplish this, a pawl, as 46, is provided. The pawl 46 is somewhat of an L-shape to provide two angularly disposed arms 47 and 48. The part of the pawl 46 at the juncture of its arms is pivoted, at 49, to the side wall 16 of the casing so that the free end of its arm 47 is in releasable engagement with the shoulder 42 of the shield element 40, and to yieldingly hold this

pawl in contact with the shoulder of the shield element a spring 50 is provided. The spring 50 may be in the form of a curved rod, or strip of metal having one of its ends secured, at 51, to the wall 13 of the casing, and the other end of the spring movably abuts against the arm 47 of the pawl 46, the spring being tensioned to normally force the pawl toward the shield element.

- 10 When the shield element 40 is disposed interiorly of the casing it is held by the pawl 46 against the tension of the spring 44 for being operated when the door is closed, and to cause the shield element to be thus actuated, through an eye 52 projecting from the wall 16 of the casing between the pawl 46 and the wall 11 of the casing is a movable rod 53 which is of a length so that one of its ends contacts with the arm 48 of the pawl 20 while its other end is movably disposed through the hole 29 of the front wall 11 so as to protrude a slight distance from the casing. On the exterior of the front wall 11 of the casing is a transversely disposed strip 25 54 of spring metal having one of its ends secured, at 55, to the front wall of the casing, and the other part of this strip is bent outwardly from the casing so that its second end is disposed over the end of the rod 53 30 which protrudes beyond the casing.

When the door is being closed and with the contacting of its free front edge with the frame of the door, the spring strip 54 will also be contacted by the frame, and with the 35 further movement of the door to a closed position the strip will engage the protruding end of the rod 53. This rod will thereby be forced inwardly of the casing for swinging the pawl 46 on its pivot so as to throw 40 the arm 47 of the pawl out of engagement with the shoulder 42 of the shield element 40. The shield element then being released will be caused by the tension of the spring 44 to be guided outwardly of the casing so 45 that its end part in the opening 27 of the casing will be removably seated in the socket 19 of the frame of the door to prevent an instrument from being inserted from the exterior of the door between the door and its 50 frame for attempting to surreptitiously operate the bolt 30 to cause the door to be unlocked.

To cause the shield element 40 to be operated, in unison with the operation of the 55 bolt 30 for unlocking the door, projecting upwardly from the end of the shield element disposed through the opening 25 of the partition 24 of the casing, is a lug or flange 56 of a height as well as being arranged in 60 abutting arrangement with the end of the bolt which is interiorly of the casing. When the bolt 30 is operated to unlock the door, as hereinbefore explained, the movement of the bolt interiorly of the casing will like-

wise cause the flange 56 and the shield element to also be guided interiorly of the casing, and when the shield element has moved a determined distance the pawl 46 will be forced by the spring 50 in a direction so that the arm 47 of the pawl will engage the shoulder 42 of the spring element. The shield element will thereby be positioned interiorly of the casing for subsequent operation, as above explained.

In the foregoing description, I have embodied the preferred form of my invention, but I do not wish to be understood as limiting myself thereto as I am aware that modifications may be made therein without departing from the principle, or sacrificing any of the advantages of this invention, therefore I reserve to myself the right to make such changes as fairly fall within the scope thereof.

Having thus described my invention, I claim as new and desire to secure by Letters Patent:—

1. The combination, in a lock, with a bolt and a shield plate both being yieldingly movable in a casing adapted to be applied to a door in opposition to two sockets whereby one end of the bolt normally protrudes beyond the casing for insertion in one of the sockets, and said bolt and plate coacting whereby the shield plate will be moved interiorly of the casing when the bolt is likewise moved, of a spring actuated pawl in the casing, releasably engaging the shield plate for normally holding the plate within the casing, a rod movable inwardly and outwardly of the casing in contact with the pawl, and a spring on the casing, operable by the closing of the door to move the rod for operating said pawl whereby the shield plate will be moved outwardly of the casing into the second socket.

2. The combination, in a lock, with a bolt and a shield plate both being yieldingly movable in a casing adapted to be applied to a door in opposition to two sockets whereby one end of the bolt normally protrudes beyond the casing for insertion in one of the sockets, the bolt and plate coacting whereby the shield plate will be moved interiorly of the casing when the bolt is likewise moved, and a spring actuated pawl in the casing, releasably holding the shield plate normally within the casing, of a rod movable inwardly and outwardly of the casing in contact with the pawl, and a spring on the casing, operable by the closing of the door to move the rod for operating said pawl whereby the shield plate will be moved outwardly of the casing into the second socket.

3. The combination, in a lock, with a bolt and a shield plate both being yieldingly movable in a casing adapted to be applied to a door in opposition to two sockets where-

by one end of the bolt normally protrudes beyond the casing for insertion in one of the sockets, of a flange on the plate contacting with the bolt whereby the shield plate will be moved interiorly of the casing when the bolt is likewise moved, a spring actuated pawl in the casing, releasably holding the shield plate normally within the casing, a rod movable inwardly and outwardly of the casing in contact with the pawl, and a spring on the casing, operable by the closing

of the door to move the rod for operating said pawl whereby the shield plate will be moved outwardly of the casing into the second socket.

15

This specification signed and witnessed this tenth day of August, A. D. 1917.
